(57) **CLAIM**

We claim the ornamental design for an electronic cigarette cartomizer, as shown and described.

DESCRIPTION

FIG. 1 is a perspective view of an electronic cigarette cartomizer according to an embodiment.

FIG. 2 is a view of a first side of the electronic cigarette cartomizer depicted in FIG. 1.

FIG. 3 is a view of a second side of the electronic cigarette cartomizer depicted in FIG. 1.

FIG. 4 is a view of a third side of the electronic cigarette cartomizer depicted in FIG. 1.

FIG. 5 is a view of a fourth side of the electronic cigarette cartomizer depicted in FIG. 1.

FIG. 6 is a view of a first end of the electronic cigarette cartomizer depicted in FIG. 1; and,

FIG. 7 is a view of a second end of the electronic cigarette cartomizer depicted in FIG. 1.

In the drawings, the broken lines depict environmental subject matter only and form no part of the claimed design.
